OTHER PUBLICATIONSU.S. Office Action dated Apr. 4, 2019, in U.S. Appl. No. 29/589,958.
(Continued)*Primary Examiner* — Andrew T Nemeth(74) *Attorney, Agent, or Firm* — Weaver Austin
Villeneuve & Sampson LLP(57) **CLAIM**

We claim the ornamental design for a display screen with a graphical user interface, as shown and described.

DESCRIPTION

FIG. 1 depicts a front view of a display screen with a graphical user interface showing a first embodiment of the design.

FIG. 2 depicts a front view of a display screen with a graphical user interface showing a second embodiment thereof.

FIG. 3 depicts a front view of a display screen with a graphical user interface showing a third embodiment thereof; and,

FIG. 4 depicts a front view of a display screen with a graphical user interface showing a fourth embodiment thereof.

The broken lines shown in the Drawings represent portions of the display screen with a graphical user interface that form no part of the claimed design.
